(57) **CLAIM**

The ornamental design for a peg support member, as shown and described.

DESCRIPTION

FIG. 1 is a front, top, right side perspective view of the peg support member, in accordance with the present invention; FIG. 2 is a rear, bottom, left side perspective view thereof; FIG. 3 is a front view thereof;

FIG. 4 is rear view thereof;

FIG. 5 is a top view thereof;

FIG. 6 is a bottom view thereof;

FIG. 7 is a right side view thereof, the left view is a mirror image thereof; and,

FIG. 8 is a perspective view of the peg support member in the environment of a peg and peg board, in accordance with the present invention.

The broken lines depict environmental structure that forms no part of the claimed design.
